John J. Stevenson, INVENTOR.

BY

Geo. P. Kimmel. ATTORNEY.

UNITED STATES PATENT OFFICE.

JOHN J. STEVENSON, OF MUSKEGON, MICHIGAN.

CLOTHES DRIER.

Application filed January 16, 1925. Serial No. 2,803.

To all whom it may concern:

Be it known that I, JOHN J. STEVENSON, a citizen of the United States, residing at Muskegon, in the county of Muskegon and 5 State of Michigan, have invented certain new and useful Improvements in Clothes Driers, of which the following is a specification.

This invention relates to improvements in 10 clothes driers, and has for one of its objects to simplify and improve the construction and increase the efficiency and utility of devices of this character.

Another object of the invention is to provide 15 a device of this character including a plurality of bars adapted to be individually adjusted horizontally to receive the garments to be supported, and collectively disposed in vertical position to occupy less 20 space when not in use.

Figure 1 is a side elevation in section on the line 1—1 of Figure 3.

Figure 2 is a front elevation with the 25 clothes suspension bars in vertical or inoperative position.

Figure 3 is a plan view, with the suspension bars extended or disposed in position to receive the garments.

The improved device includes a support 30 or base formed of a plate 10 adapted to be attached to a wall or the like indicated at 11, by screws 12 or other fastening devices.

The plate 10 is formed with a relatively large opening indicated at 13, and extending 35 forwardly from the plate at the ends of the opening are arms 14, each having a longitudinal slot 15. Extending from the base plate 10 at the upper edge of the opening 13 is a forwardly directed downturned 40 stop lip or catch 16, as shown.

A head member forms a part of the improved device, and includes spaced portions 45 18 and 19 and connecting portion 17, the portion 19 extending in advance of the portion 18, as indicated.

Depending from the portion 19 of the head member are perforated ears 20 through which a pivot pin 21 extends with the terminals extending through the slots 15, with 50 the outer ends enlarged as shown at 22, to prevent the separation of the pin from the slots and ears.

By reference to Figures 2 and 3 it will be noted that recesses 23 are formed in the 55 ends of the opening 13 to permit the heads

22 of the pin 21 to pass when the head member is disposed in position.

The portions 18 and 19 of the head member are provided with a plurality of aligned apertures to receive cotter pins 24, or the like, to each of which a garment supporting bar 25 is swingingly coupled and operative between the spaced head members.

Extending from the portion 18 of the head member is an outwardly curved lip 26 to engage beneath the catch 16, as shown more clearly in Figure 1. By this means the head member together with its suspension bars 25 may be tilted on the pivot pin 21 and the latter adjusted in the slot 15 and the catch 26 inserted beneath the lip 16, and the head and its bars thus retained in horizontal position, and the bars adjusted laterally to any required extent on their pivots 24.

In assembling this drier, the head member with the bars 25 removed therefrom, is inserted through the aperture 13 formed in the plate 10, with the open side of the head entering first through the aperture. 80 The pivot pin or bar 21 having been previously fixed in the ears 20 which depend from the lower side of the head, will enter the open ends of the slot 15 formed in the arms or extended portions 14. The head 85 will then ride forward upon the extended portions until the upstanding lip at the rear of the head abuts the depending lip 16 formed upon the plate 10. The ends of the bars 25 can now be placed in position in 90 the head and the cotter pins or holding devices 24 passed therethrough to secure the bars in position.

When the device is not required for use the bars 25 may be swung together in substantially parallel relation and by slightly 95 tilting upwardly the outer ends of the bars the lip 26 can be disengaged from the catch 16. The pins 21 are then drawn along the slots 15 with the head and bars until the lip 26 is free from the catch 16, when the bars and head can be dropped into the position represented in Figure 2.

The improved device is simple in construction, can be inexpensively manufactured, partly of wood and partly of metal, or wholly of metal.

The supporting plate and its slotted arms can be of cast aluminum, while the head member together with its ears 20 may also 110

be of a single casting of aluminum or the like.

For the purpose of illustration the device is shown with four of the garment suspension bars 25, but the head member may be constructed to hold any required number of the bars.

The preferred embodiment of the invention is disclosed in the drawings and set forth in the specifications, but it will be understood that modifications within the scope of the claims may be made in the construction without departing from the principle of the invention or sacrificing any of its advantages.

Having thus described the invention, what is claimed as new is:—

1. A device of the character described comprising, a base member having an opening therethrough, a forwardly and downwardly directed lip at the top edge of said opening, longitudinally slotted spaced arms extending from said base one on each side of said opening and having the slots therein merging with said opening, rack bars, a holder for said bars, a lug at the rear of said holder adapted to engage under said

lip, spaced depending ears carried by said holder, and a rod having a head upon each end, carried by said ears and engageable in said slots, the heads of said rods bearing against the outer faces of said arms.

2. A device of the character described comprising, a base member having an opening therethrough, a forwardly and downwardly directed lip at the top edge of said opening, longitudinally slotted spaced arms extending from said base one on each side of said opening and having the slots therein merging with said opening, rack bars, a holder for said bars, a lug at the rear of said holder adapted to engage under said lip, spaced depending ears carried by said holder, and a rod having a head upon each end, carried by said ears and engageable in said slots, the heads of said rods bearing against the outer faces of said arms, said holder and rod carried thereby being adapted to pass through said opening, when assembling the device, the said rod ends entering the open ends of said slots.

In testimony whereof, I affix my signature hereto.

JOHN J. STEVENSON.
